BULLET-RESISTING STRUCTURE

Oliver B. McClintock and Ferdinand A. Gabbert,
Minneapolis, Minn., assignors to O. B. McClintock Company, Minneapolis, Minn., a corporation of Minnesota

Application May 18, 1931, Serial No. 538,080

11 Claims. (Cl. 89—36)

This invention relates to means for protecting banks and like places for the deposit of valuables against a daylight hold-up by a bandit.

5 The present invention provides a bullet-resisting structure for the exposed side or sides of a teller's cage or like enclosure to protect the person or persons in the enclosure as well as the valuables. The structure includes one or 10 more substantially duplicate assemblies for each cage or teller in an enclosure. Each assembly includes a bullet-resisting wicket which may be opened from the inside of the closure to permit the passing of bulky articles or packages 15 through the opening.

Said assembly further includes a bullet-resisting deal tray, preferably mounted in the wicket, and provides for the passing of small articles through the structure such as pass books, 20 checks, currency, etc. This deal tray is the subject matter of a copending application filed in the name of the inventors Edward C. Hanson and Sylvan R. Popp of date May 16, 1931, under Serial Number 537,770 and assigned to the O. B. 25 McClintock Company, a Minnesota corporation, as well as the present application.

The assembly still further includes one or more bullet-resisting voice panels, preferably forming a part of the wicket which permit persons on opposite sides of the structure to converse in moderate tones.

Bullet-resisting transparent inserts in the structure and wicket afford full vision for persons on opposite sides of the structure. Closely 35 associated with certain of these transparent inserts are normally closed gun ports.

The bullet-resisting structure in addition to giving full protection to the person or persons in the teller's cage or enclosure, puts a bandit 40 to a decided disadvantage, in case he attempts to hold-up the bank for the reason that the gun ports are so located in the bullet-resisting structure as to permit the bandit to be covered, in any position he may assume in the lobby, by a firearm in the hands of the person 45 in the cage.

To the above end, generally stated, the invention consists of the novel devices and combinations of devices hereinafter described and 50 defined in the claims.

In the accompanying drawings, which illustrate the invention, like characters indicate like parts throughout the several views.

Referring to the drawings:

55 Fig. 1 is a front elevation of typical assem-

blies for an enclosure for several tellers, the center assembly is completely shown while the adjacent assemblies are only fragmentarily illustrated;

Fig. 2 is a view partly in plan and partly in horizontal section taken on the line 2—2 of Fig. 1;

Fig. 3 is a fragmentary view in section taken on the line 3—3 of Fig. 1, on an enlarged scale;

Fig. 4 is a fragmentary detail view in section 10 taken on the line 4—4 of Fig. 1, on an enlarged scale;

Fig. 5 is a view partly in elevation and partly in section taken on the line 5—5 of Fig. 1;

Figs. 6 and 7 are views principally in section 15 taken on the lines 8—8 and 9—9, respectively, of Fig. 1 on an enlarged scale, some parts being broken away; and

Fig. 8 is a view principally in section taken on the irregular line 10—10 of Fig. 1, on an enlarged scale.

The numeral 11 indicates a counter structure which separates what may be assumed to be a teller's cage or enclosure from a bank lobby and which structure extends to the floor and has a 25 relatively wide top. Mounted on the counter is a skeleton structure comprising columns 12, lower horizontal rails 13, on the top of said counter between the columns 12, and a cornice 14 supported on the columns 12. Gaps are formed in 30 the lower rails 13 midway between adjacent columns for wicket openings, as will hereinafter appear. The columns 12 divide the counter into individual work spaces for tellers.

The above described elements may form a part 35 of the bank fixtures at the time our bullet-resisting structure is installed or form a part of the bullet-resisting installation. In case the counter structure forms a part of the bank fixtures the same will be lined with a bullet-resisting substance or material but for the purpose of this case, it will not be necessary to illustrate the same.

The bullet-resisting structure, as shown, is 45 made up of a plurality of units or assemblies substantially identical, the one with the other, and there is one of these assemblies for each work space between adjacent columns 12. It is important to note, by reference to Fig. 2, that the several assemblies are continuously formed, the one with the other, so that there is no gap or unprotected portion back of the columns 12.

Each bullet-resisting assembly comprises an outer series of relatively wide upright panels 50

55

positioned to leave intervening spaces 16 and an inner series of relatively narrow upright panels 17 also positioned to leave intervening spaces 18. These panels 15 and 17 are formed from 5 steel plates and the two series of panels 15 and 17 are staggered so that the panels 17 are directly back of the spaces 16. Each panel 15-17 is channel-shaped in cross-section, relatively shallow and the flanges of the panels of the two 10 series are turned toward each other. The width of the inner panels 17 is greater than the width of the spaces 16 so that the flanges of the outer panels 15 are between the flanges of the inner panels 17 and laterally spaced therefrom. The 15 panels 15 and 17 are laterally spaced so that their flanges do not interlap and leave passages therebetween. This arrangement of the two series of panels 15 and 17 and their flanges 20 form circuitous transverse passages through the bullet-resisting structure.

The two series of panels 15 and 17 are rigidly held in assembled relation by a lower channel bar 19 and an upper channel structure 20. The flanges of the channel bar 19 and channel structure 25 20 are turned toward each other and the end portions of said panels extend into their channels to the webs thereof.

The web of the channel 19 rests directly on 30 the counter 11 and is secured thereto by screws and the channel structure 20 on the back of the cornice 14 comprises longitudinally separable members connected by screws 21 and one of said members is secured by screws to the cornice 14, see Figs. 6 and 7.

35 In assembling the structure the panels 15 of the outer series are secured to the outer flanges of the channel 19 and channel structure 20 by screws 22 and thereafter the panels 17 of the inner series are secured to the inner flanges of 40 the channel 19 and channel structure 20 by screws 23. The separable channel structure 20 permits this assembly of the panels 15 and 17. By reference to Fig. 4, it will be noted that the 45 wide outer panels 15 are provided with horizontal slots through which the screws 22 project and the purpose thereof is to permit said panels to be edgewise adjusted and position the same so that the intervening spaces are all of the same width.

50 Formed in the central panels 15 and 17 is a wicket opening 24 which extends to the top of the counter 11 and is in registration with the passage through the lower rail 13. This opening 24 at its sides and top is surrounded by a 55 metallic frame 25 rigidly secured to the channel bar 19, which has a gap therein the width of said opening 24, and to the panels 15 and 17.

A wicket 26 is mounted in the wicket opening 24 and hinged at 27 to the frame 25 for inward 60 swinging movement over the counter 11. This wicket 26 is normally held closed by a lock 28 operable only from the inside of the enclosure. The bottom portion of the wicket 26, at its intermediate portion, is open to leave a passage 65 29 in which is mounted a deal tray 30. This deal tray 30, which is the subject matter of a co-pending application heretofore identified, comprises an outer casing 31 and a rotatable inner casing 32, the former of which is rigidly secured 70 to the wicket 26 in the passage 29 and the latter of which is rotatably mounted in said outer casing and a handle 33 is provided for manipulating the same.

The fixed casing 31 is provided with a passage 75 on each side of the bullet-resisting struc-

ture and the casing 32 is provided with a single passage arranged to be alternately brought into registration with the passages in the fixed casing 31 by the rotation of said inner casing. The handle 33 is provided with a lock 34 for holding the rotatable casing 32 with its passage in registration with either of the passages in the fixed casing 31. In the top of the rotatable casing 32 is a bullet-resisting glass insert 35 that is diametrically opposite the passage in said casing. The bottoms of the casings 31 and 32 are open and closely positioned to the top of the counter 11 so that a pass book, check, currency or the like may be moved on the top of the counter 11 through the deal tray 30. The wicket 26 may be opened so that large packages may be passed through the opening normally closed thereby.

Mounted in the central portion of the wicket 26 directly over the deal tray 30 is a large bullet-resisting glass insert 36 and on each side of said insert is a bullet-resisting voice panel 37 which permits persons on opposite sides of the wicket 26 to converse in moderate tones and at the same time have a clear vision 25 through the insert 36.

Each voice panel 37 includes a series of outer, intermediate and inner upright bars 38, 39 and 40, respectively, with intervening spaces in each series. The bars 38, 39 and 40 in the several 30 series are staggered, as shown in Fig. 3, and form circuitous passages through the structure. The bars 38 are V-shaped in cross-section with their apexes turned outward and the bars 40 are channel-shaped in cross-section with their flanges turned toward the structure. All the bars forming the voice panels 37 are of steel and the arrangement thereof is such as to completely close any opening through said panels which a ricochetting projectile may find. It will be noted that at no point through the voice panels do direct openings exist or one which would permit lead spatter or a ricochetting projectile to pass.

The circuitous transverse passages between 45 the panels 15 and 17 and through the voice panels 37 permit free circulation of air so that the protecting partition does not in any way interfere with the ventilation of the enclosure.

50 Formed in the wide panels 15 on each side of the wicket 26 is an opening 41 closed by a bullet-resisting glass insert 42. The glass inserts 42 as well as the glass insert 36 by virtue of their transparency assist in the distribution 55 of light throughout the banking room and provide adequate visibility through the protecting partition. These glass inserts 42 are held in place by channels 43 on the inner face of the respective panels 15 at the bottoms and sides thereof and into which channels said inserts are slipped from the upper ends of the openings 41. Angle plates 44 detachably secured by bolts to the channels 43 overlie the upper ends of the inserts 42 and hold the same in place and prevent lifting thereof, see Fig. 7.

55 Formed in the wide panels 15 under each glass insert 42 is a round gun port 45. Each gun port 46 is normally closed by a steel slide 46 mounted in ways 47 on the sides of said port for vertical sliding movement and with freedom to close by gravity. A gravity-actuated latch 48 and a cooperating horizontal latch bar 49 normally holds the slide 46 closed, see Fig. 7. The latch bar 49 is secured to the ways 47 70 75

above the gun port 45 and outward of the slide 46. The latch 48 is loosely secured at its lower end portion to the lower end of the slide 46 by a pair of screws with freedom for a limited 5 lateral swinging movement toward and from the slide 46.

On the lower end of the latch 48 is a laterally and outwardly projecting lip 50 arranged to be engaged by the muzzle end of a firearm 10 X and lifted to first swing the latch 48 into an inoperative position so that it will pass the latch bar 49 and further lifting movement on the lip 50 will cause the slide 46 to move upward in the ways 47 to open the gun port 45 so that 15 the barrel of the firearm X may be projected through said port and at the same time hold the slide 46 in a raised position. When the firearm X is withdrawn from the port 45 the slide 46 will drop by gravity and again close 20 the gun port 45. At the time the slide 46 reaches its closed position the latch 48 will be automatically moved by gravity under the latch bar 49 and lock the slide 46 closed. Of course, 25 the slide 46 may be opened and held open by hand instead of using the firearm X.

Spikes 51 are mounted on the top of the cornice 14, project upwardly and forwardly therefrom and their function is to prevent a person from vaulting over the fixtures or securing 30 a hand-hold on the top thereof that would permit his climbing to the counter and firing over the protected area.

What we claim is:

1. A structure of the class described having a 35 voice panel comprising a frame, front, rear and intermediate series of bars with intervening spaces between the bars of the several series, the bars of the back series being substantially directly back of the bars of the front series and 40 the bars of the intermediate series being staggered in respect to the bars of the front series whereby the bars of the intermediate series are back of the spaces between the bars of the front series.

2. The structure defined in claim 1 in which the bars of the front series are V-shaped in cross-section with their flanges turned toward the bars of the back and intermediate series.

3. A bullet-resisting structure comprising a 50 series of upright outer panels and intervening spaces, and a series of upright inner panels and intervening spaces, the panels of the two series being laterally spaced and staggered, whereby the panels of the inner series are directly back 55 of the intervening spaces of the outer series, the bodies of the outer panels being substantially flat and in substantially the same vertical plane, said outer panels having on their longitudinal edge portions inturned flanges that are 60 relatively shallow, said inner panels being channel-shaped in cross-section with their flanges turned toward the outer panels.

4. The structure defined in claim 3 in which the outer panels are relatively adjustable to vary 65 the width of the intervening spaces.

5. The structure defined in claim 1 in which

the bars of one series are V-shaped in cross-section.

6. A bullet-resisting hollow structure having a face member and a back member, each of said members having a voice opening, a pair of laterally spaced V-bars arranged with their apexes at the voice opening in one of said members and with their flanges in diverging relation to the plane thereof, and a single bar between the V-bars and the other of said members and spaced therefrom in overlapping arrangement with the inner flanges of the V-bars. 10

7. The structure defined in claim 6 which further includes a pair of bars spaced outwardly of the hollow structure in overlapping arrangement with the single bar and one of said members at its voice opening. 15

8. The structure defined in claim 6 which further includes a pair of channel bars spaced outwardly of the hollow structure with their flanges turned toward the same in overlapping arrangement with the single bar and one of said members at its voice opening. 20

9. A structure of the class described having a voice opening at each side thereof and a baffle including three bars, two of which are V-shaped in cross-section, said bars being spaced from each other and from the structure and forming a circuitous voice passage leading from one voice opening to the other, said baffle further 25 including a pair of channel bars spaced from each other and from the structure. 30

10. A bullet-resisting hollow structure having a face member and a back member spaced, the one from the other, each of said members having a voice opening, and a V-bar baffle between 35 said members with its apex at the opening in one of said members and with its flanges in diverging relation to the plane thereof, the flanges of the V-bar baffle being in overlapping arrangement with other parts of the structure and cut off a direct passage through the structure from one voice opening to the other. 40

11. A bullet-resisting hollow structure having a face member and a back member spaced, the one from the other, each of said members having a voice opening, and a baffle including three 45 bars, two of which are V-shaped in cross-section and laterally spaced with their apexes at the opening in one of said members and with their flanges in diverging relation to the plane thereof, the outer flanges of the two V-bars being in overlapping arrangement with said members and cut off a direct passage through 50 said structure from one voice opening to the other outwardly of each V-bar, the other or third bar being between the V-bars and one of said members and spaced therefrom, the inner flanges of the V-bars being in overlapping 55 arrangement with said third bar and cut off a direct passage between the V-bars from one opening to the other. 60
